US0D1032651S

(12) **United States Design Patent** (10) Patent No.: **US D1,032,651 S**
(45) Date of Patent: ** Jun. 25, 2024

(54) **DISPLAY SCREEN OR PORTION THEREOF WITH GRAPHICAL USER INTERFACE**

- (71) Applicant: **Apple Inc.**, Cupertino, CA (US)
- (72) Inventors: **Mario Azzi**, Smithtown, NY (US); **Anton Davyдов**, Gilroy, CA (US); **Alan C. Dye**, San Francisco, CA (US); **Nicholas Felton**, Cupertino, CA (US); **Aurelio Guzmán**, San Jose, CA (US); **Stephen O. Lemay**, Palo Alto, CA (US); **Alexander Charles MacLean**, San Jose, CA (US); **Wyatt R. Mitchell**, San Francisco, CA (US); **Marcel van Os**, San Francisco, CA (US); **Christopher Wilson**, San Francisco, CA (US)
- (73) Assignee: **Apple Inc.**, Cupertino, CA (US)
- (**) Term: **15 Years**
- (21) Appl. No.: **29/836,913**
- (22) Filed: **Apr. 29, 2022**

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 shows a display screen or portion thereof with graphical user interface showing our new design; and, FIG. 2 shows another embodiment thereof.

The peripheral dashed broken lines illustrate a display screen or portion thereof, and form no part of the claimed design.

**1 Claim, 1 Drawing Sheet
(1 of 1 Drawing Sheet(s) Filed in Color)**
